UNITED STATES PATENT OFFICE.

JOHN HOUPT, OF SPRINGTOWN, PENNSYLVANIA.

COMPOUND FEED-PUMP FOR STEAM-BOILERS.

SPECIFICATION forming part of Letters Patent No. 285,622, dated September 25, 1883.

Application filed April 23, 1883. (No model.)

To all whom it may concern:

Be it known that I, JOHN HOUPT, of Spring-
town, in the county of Bucks and State of
Pennsylvania, have invented certain new and
useful Improvements in Compound Feed-
Pumps for Steam-Boilers, of which the fol-
lowing is a full, clear, and exact description.

This invention relates to hot-water-feed
pumps for steam-boilers, constructed to oper-
ate upon the same general principles as the
pump described in reissued Letters Patent
No. 10,177, granted me August 8, 1882, and
has a like object in view—namely, the supply-
ing of steam-boilers, with hot water at a high-
er temperature, and with a greater uniformity
of pressure than is practicable with feed-
pumps of ordinary construction, thus econ-
omizing fuel, and tending to prevent explo-
sions due to the water becoming too low in
the boiler in consequence of the defective
working of the hot-water-feed pump, and
which is most liable to occur when the water
accidentally attains a very high temperature
in the heater, more especially the heater of a
high-pressure engine.

In the present invention, as in my previous
one above referred to, the force-pump which
supplies the water to the boiler has combined
with it an auxiliary pump, with check-valve
between them, said auxiliary pump being ar-
ranged between the first-named pump and the
heater, and both pumps working simultane-
ously in like directions to produce an artifi-
cial pulsation and overcome any undue back-
pressure in the cylinder and supply-pipe; but
I simplify the construction by using elon-
gated plungers in said pumps, instead of pis-
tons having valves in them, as also in other
respects; and my invention is embodied in the
construction and combination of parts, sub-
stantially as hereinafter shown and described.

Reference is to be had to the accompanying
drawings, forming part of this specification,
in which similar letters of reference indicate
corresponding parts in all the figures.

Figure 1 represents a vertical section of my
improved compound hot-water-feed pump for
steam-boilers. Fig. 2 is a horizontal section
of the same on the irregular line xx in Fig.
1; and Fig. 3 is a further horizontal section,
in part, upon the line yy , Fig. 1.

A in the drawings indicates the vertical
cylinder of the feed-pump proper, provided
with an elongated plunger, B, arranged to
pass out through the bottom or one end of 55
said cylinder, and of the same diameter, or
thereabout, throughout its entire length as
the interior of such cylinder. C is the deliv-
ery-valve of said pump, arranged at the up-
per or discharge end of the cylinder A, with-
in or under cover of an outlet branch, D, which
connects with the boiler.

EE' indicate the hot-water-supply pipe or
passage to the upper or discharge end of the
cylinder A from the cylinder F of the auxil- 65
iary pump. This passage, within which is
the spring check-valve G, is partly formed
within or through a plug-seat, H, for said
valve, arranged within a chamber, I, such
seat being held to its place in said chamber 7c
by set-screws b b, whereby the check-valve
and its seat may be readily taken out for re-
pairs.

The inner or upper end of the plunger B is
constructed with a projection, c, which enters 75
within the aperture closed by the outlet or
discharge valve C, whereby said plunger in
its upstroke is made to work close up to the
said valve when closed.

J is the elongated plunger of the auxiliary 8c
pump, arranged to pass out through the upper
end of the cylinder F, and K is the inlet of the
auxiliary pump, fitted with an inlet valve, L.

M is the tube, having a regulating-cock, d,
which connects the auxiliary pump with the 85
heater or source of supply that is not shown,
but which, in practice, is arranged above the
level of the pump-cylinder A, so that the
pump will be always primed and supplied by
the gravitation of the feed-water itself, inde- 9c
pendent of the pressure of the atmosphere.

Both plungers B J reciprocate together and
in the same direction simultaneously, and by
making them hollow they may be worked from
any suitable mechanism by rods ee, pivoted 95
within them, as shown by dotted lines in Fig. 1.

The general action is the same as in the
compound pump described in reissue Letters
Patent No. 10,177, hereinbefore referred to,
both plungers reciprocating together and in
the same direction, and keeping up a constant
supply of hot water, and producing an arti-

ficial pulsation, which overcomes any undue back-pressure that may arise from the formation of steam in the pump-cylinder and supply-pipes owing to the high temparture attained by the surrounding materials, so that it is practicable to supply a steam-boiler with water of higher temperature than by means of the ordinary feed-pump, by reason of there being greatly less danger of explosion from the rapid formation of steam in the cylinder and supply-pipes.

Having thus described my invention, what I claim as new, and desire to secure by Letters Patent, is—

- 15 1. In a pump for feeding hot water to steam-boilers, the combination of the cylinder A, opening upward, and having the valve D and the elongated plunger B, with the supply passage or pipe E E', within which is located the valve G, and the cylinder F, opening downward, and having the elongated plunger J, the latter cylinder and plunger being arranged intermediately between the supply end and discharge end of the pipe and the former cylinder and plunger, substantially as and for the purpose set forth.
- 20 2. In a pump for feeding hot water to steam-

boilers, the combination, with the cylinder A, the elongated plunger B, and the outlet and check valves C G, of the auxiliary feed-pump, 30 consisting of cylinder F, elongated plunger J, and valve L, the plungers B and J being adapted to perform their strokes simultaneously in the same direction, substantially as specified.

35

3. The externally-removable plug valve-seat H, check-valve G, and chamber I, in combination with the pump-cylinders A F, the elongated plungers B J, the valves C L, and the ducts or passages D, E, E', and K, essential- 40 ly as and for the purposes herein set forth.

4. In a pump for feeding hot water to steam-boilers, the combination of the hollow elongated plungers B J, with their operating-rods e e, the pump-cylinders A F, the valves C, G, 45 and L, the passages D E E' K, the externally-removable plug valve-seat H, with its chamber I, and the tube M, with its regulating-cock d, substantially as shown and described.

JOHN HOUTP.
